[57] **ABSTRACT**

A drapery sizer and a seam and return or overlap re-

gistering system. The drapery sizer includes upper and lower frames carrying upper and lower fingers proportioned and designed to receive therebetween portions, respectively, of the upper and the lower edges of a drapery. The upper fingers define pleat receiving spacers therebetween and the lower fingers are proportioned and designed to engage therebetween lengths of the lower edge portion corresponding respectively to the pleats. Indicia means are placed on the lower fingers to identify positions thereon corresponding respectively to predetermined positions on the pleats. The registering system includes first means for registering the identity of each pleat in which each vertical seam of the drapery appears, second means for registering the position at which such a seam appears in such a pleat, and third means for registering the depth of the return or overlap at the upper edge portion of the drapery together with cooperating control means for determining and registering the amount of return or overlap at the lower edge portion of the drapery.

SEAM LOCATOR FOR SIZING DRAPERIES

This invention is in the field of drapery sizing.

To my knowledge, no one has heretofore devised, for use with conventional drapery sizing equipment, means for registering the identity of each pleat in which each vertical seam of the drapery appears, means for registering the position at which such a seam appears in such a pleat and means for registering the depth of the return and overlap at the upper edge portion of the drapery together with cooperating control means for determining and registering the proper amount of return and overlap at the lower edge portion of such a drapery.

I refer to my prior U.S. Pat. No. 2,699,010 issued Jan. 11, 1955. This prior patent discloses and claims a drapery sizer which has been widely used in the drapery cleaning industry and which has significantly improved the manner in which drapes appear after cleaning and sizing and which has significantly reduced the amount of time required to clean and size a drapery. My drapery sizer includes a cabinet, upper and lower frames disposed in the cabinet, at least one of the frames being shiftable selectively to determine the spacing therebetween for sizing draperies to the proper length and means for shifting the frames. Usually, and in accordance with my prior invention, the upper frame is vertically movable relative to the lower frame. The upper frame carries a plurality of laterally spaced apart first fingers for engaging the upper edge portion of a drapery and the lower frame carries a plurality of laterally spaced apart second fingers for engaging the lower edge portion of such a drapery, the first fingers defining pleat receiving spaces therebetween proportioned and designed so that adjacent pleats of such draperies are disposed respectively in adjacent spaces, and the second fingers being proportioned and designed to engage therebetween lengths of such lower edge portion corresponding respectively to the pleats. My present invention comprises a seam locating system including indicia means placed on the said second fingers identifying positions thereon corresponding respectively to predetermined positions on such pleats, a plurality of first means for registering the identity of each pleat in which each vertical seam of such a drapery appears, and a plurality of second means for registering the position at which such a seam appears in such a pleat. My present invention also may comprise a plurality of third means for registering the depth of the return or overlap at the upper edge portion of such a drapery and cooperating control means for determining and registering the proper amount of return or overlap at the lower edge portion of such a drapery, the control means being operatively connected to and operated respectively by the said third means.

It is an object of my present invention significantly to reduce the amount of time required to install properly a drapery in a sizing apparatus by giving the operator a registering and computing device which will register certain required information as the operator connects the upper portion of the drapery to the upper frame and then provide the proper information when the operator is connecting the lower edge portion of the drapery to the lower frame. It will be appreciated by those skilled in the art and familiar with equipment such as disclosed in my said prior U.S. Pat. No. 2,699,010 that there may be a considerable time dif-

ferential between the connection of the top of the drapery to the upper frame and the connection of the bottom of the drapery to the lower frame, that there is a considerable amount of difficulty in relating the amount of overlap of the lower fingers to the number and spacing of the pleats at the upper edge of the drapery, and that the proper amount of return or overlap at the lower edge portion of the drapery is difficult for operators to determine. With the indicia means that I place on the overlapping fingers of the lower frame, operators of my drapery sizers using my present invention can accurately locate each vertical seam of the drapery relative to the overlapping fingers and they can quickly and accurately make the proper return or overlap settings at the lower edge portion of the drapery.

Other objects and features of my present invention will become apparent as this description progresses.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

In the drawings:

FIG. 1 is a fragmentary plan view of my registering system;

FIG. 2 is a fragmentary sectional view taken from FIG. 1 generally along the lines 2—2;

FIG. 3 is a diagrammatical view of a conventional drapery pleat showing various predetermined locations thereon, each of which is assigned a location number;

FIG. 4 is a fragmentary, sectional plan view of the upper frame of a drapery sizer showing how the upper edge portion of a drapery is engaged by the fingers carried on the upper frame;

FIG. 5 is a fragmentary, sectional plan view of the lower frame of a drapery sizer showing the overlapping fingers carried on the lower frame and the manner in which the lower edge portion of the drapery is engaged by the overlapping fingers;

FIG. 6 is an enlarged, fragmentary view showing the overlapping fingers of the lower frame with indicia means identifying positions thereon corresponding respectively to the predetermined positions as shown in FIG. 3; and

FIG. 7 is a fragmentary sectional view showing, diagrammatically, the sizing of a drapery and particularly the relationship of a lower edge portion of the drapery relative to the upper edge portion of the drapery.

Referring first to FIG. 3, it will be seen that I have illustrated diagrammatically a conventional drapery pleat. It will be appreciated that a plurality of such pleats are provided along the upper edge of conventional draperies. I have assigned position identification numbers 1-8, respectively, to eight different positions on the length of the drapery material which comprises the pleat and the material on each side of the pleat. The manner in which pleats are formed and sewn is well known and need not be discussed, in detail, herein. My present invention is not limited to a particular type of pleat in that I can assign such position identification numbers to any type of conventional pleat. Each of these positions 1-8 corresponds to a position on the lower edge of the drapery such that, if the pleat were

taken out of the upper edge of the drapery, a straight vertical line could be drawn from each position 1-8 at the upper edge of the drapery to its corresponding position at the lower edge of the drapery. It will be appreciated, therefore, that the upper edge portion of a drapery is pleated or gathered and that the lower edge portion of the drapery is much fuller or greater in length.

When a drapery is sized, each segment of the lower edge portion of the drapery corresponding to a pleat in the upper edge portion of the drapery must be held in vertical registry with the pleat so that the draperies will hang straight or vertically when taken out of the sizer and again mounted on the usual traverse rods.

Many draperies are quite large and formed by sewing together panels of drapery material. Then, the upper edge portion of the drapery is pleated. The vertically extending seams between the panels then appear either in a pleat or in the spaces between a pleat. It is of the utmost importance to the proper sizing of a drapery that these seams be sized or pulled perfectly straight. If they are not, the appearance of the drapery, after sizing, will be entirely unsatisfactory.

A drapery sizer is completely disclosed in my said prior U.S. Pat. No. 2,699,010. The following description is directed toward those parts of a drapery sizer which work in conjunction with my present invention.

The drapery sizer includes a cabinet, walls of which are indicated by the reference numeral 20, and an upper frame 22 disposed in the cabinet for generally vertical reciprocation. The upper frame carries a plurality of laterally spaced apart first fingers 24 for engaging the upper edge portion of a drapery, the illustrated fingers 24 having distal ends engageable with a support member 26 and their proximal ends mounted for pivotal movement about a horizontally extending rod 28 carried on the frame 22. As disclosed in my said prior patent, each finger 24 may be proportioned and designed to pivot downwardly as indicated by the arrow 25 so that its distal end will engage and hold a portion of the drapery against the support member 26. Further, the fingers 24 are loosely mounted on the rod 28 such that they are axially movable along the rod. Means, not shown, is provided for urging the fingers 24 together as indicated by the arrow 30 to grip the portions of the drapery disposed between the fingers.

The entire frame 22 is movable vertically upwardly to a selected height corresponding to the height of the drapery, the frame 22 being guided, for instance, by means such as the guide member 32 which extends through a vertically extending slot 34 in the cabinet wall 20 (FIG. 4).

The specimen drapery in the drawings is indicated by the reference numeral 40 and it is folded to have what is referred to as returns or overlaps 42, 44. The upper edge portion of the drapery 40 is provided with a plurality of pleats formed in accordance with the drawing of FIG. 3.

The first fingers 24 define pleat receiving spaces 48 therebetween proportioned and designed so that adjacent pleats of the drapery 40 are disposed respectively in adjacent spaces 48. This is clearly illustrated in FIG. 4.

The drapery sizer includes a lower frame 50 which is disposed below and in vertical registry with the upper

frame 22, the lower frame carrying a plurality of second fingers. In the illustrative embodiment, the second fingers include a plurality of overlapping fingers 52, 54 mounted, respectively, for pivotal movement about their proximal ends on parallel and horizontally extending rods 56, 58. The distal ends of the overlapping fingers 52, 54 rest upon a support member 60 (FIG. 7).

The amount of overlap of the fingers 52, 54 is provided by a drive mechanism including, for instance, the drive screw 62 which is driven by a drive shaft 63 and a worm 64 carried by the drive shaft. Particularly, the spacing between the two rods 56, 58 and, consequently, the amount of overlap of the fingers 52, 54 is provided by selectively adjustable movement of the fingers as indicated by the arrow 65.

The lower edge portion of the drapery 40 is disposed about the distal ends of the fingers 52, 54 as illustrated in FIG. 5. The amount of overlap of the fingers 52, 54 is determined by the number, size and spacing of the pleats at the upper edge of the drapery.

The second fingers 52, 54 are proportioned and designed to engage therebetween lengths of the lower edge portion of the drapery 40 corresponding respectively to the pleats. The length of drapery wrapped about the distal end of each finger 52 corresponds, respectively, to the drapery wrapped around the distal end of the corresponding finger 24 and the length of drapery wrapped around the distal end of each finger 54 corresponds respectively to the length of drapery formed in the pleat in the corresponding space 48.

After the lower edge portion of the drapery 40 is folded about the distal ends of the fingers 52, 54 as shown in FIG. 5, then the fingers are pressed together by means (not shown) applying a force in the direction of the arrow 50 so that the lower edge portion of the drapery is tightly connected to the frame 50 while the upper edge portion of the drapery is tightly connected to the frame 22. At that point, as disclosed in my said prior patent, the cabinet is closed and steam is admitted thereto while the two frames 22, 50 are held at the desired distance apart to provide the proper drapery height. After the steam is applied for a desired amount of time, the steam is shut off and dry air is admitted to the cabinet to dry the draperies.

One objective of my present invention is to provide means to assure that the vertical seams of a drapery are held properly during the sizing operation so that the drapery will hang straight. A vertical seam will appear at or adjacent to one of the numbered positions relative to a pleat shown in FIG. 3. In an extremely large drapery, there may be several vertical seams. Thus, the operator of the drapery sizer must know the identity of each pleat in which a seam appears as well as the position of the seam in such a pleat. My present invention comprises first means for registering the identity of each pleat in which such a vertical seam appears and second means for registering the position at which such a seam appears in such a pleat. My registering system includes indicia means placed upon the second fingers 52, 54 as illustrated in FIG. 6. The numbered positions on the fingers 52, 54 in FIG. 6 correspond respectively to the numbered positions in FIG. 3. If a vertical seam appears at any one of the numbered positions shown in FIG. 3 in or adjacent a pleat, then the seam must ap-

pear adjacent the same numbered position on the corresponding fingers 52, 54 therebelow. For instance, if a seam appears in position number 3 in a pleat at the upper edge of the drapery 40, then, in order for that drapery to be properly sized, the seam must appear adjacent the position number 3 on the finger 54 in vertical registry with the space 48 in which the pleat is disposed.

My present invention also includes third means for registering the amount of return or overlap 42, 44 at the top of the drapery and cooperating control means for determining and registering the amount of return or overlap at the bottom of the drapery. Particularly, the control means determines the amount that each return or overlap is to be increased or decreased with respect to normal at the bottom of the drapery. Whether the overlap or return is to be increased or decreased at the bottom of the drapery depends upon the size of each pleat, the spacing between pleats and, consequently, the overlapping of the fingers 52, 54.

Referring now to FIGS. 1 and 2, it will be seen that my registering system includes a vertically elongated box 71, the vertical length of which may be selected to suit the particular sizer. The box includes a front face which is visible to the operator of the sizer, which front face is provided with a plurality of spaced apart vertically elongated slots through which manually movable wheels partially extend and a plurality of spaced apart apertures as will be discussed hereinafter. In accordance with the illustrative embodiment of FIGS. 1 and 2, there is provided means for registering information concerning eight seams, and the front face of the box 71 is printed or otherwise marked to show identification of seams 1-8. For each of seams 1-8, there is a first means for registering the number of the pleat in which the seam appears and second means for registering the position (FIG. 3) at which such a seam appears in the pleat. Each illustrative first means includes a first wheel or rotor means 72 associated with the upper frame 22 and a first wheel or rotor means 74 associated with the lower frame 50, carrier means 75 trained about the wheels 72, 74 and means, such as the front face of the box 71, providing a first upper aperture 76 associated with the upper frame and a first lower aperture 78 associated with the lower frame. The carrier means 75 carries pleat-identifying indicia spaced along its length so that the indicia visible through the upper aperture 76 corresponds to the indicia visible through the corresponding lower aperture 78.

Then, in the illustrative embodiment, each second means includes a second such wheel or rotor means 80 associated with the upper frame 22 and a second such wheel or rotor means (not shown) associated with the lower frame 50, carrier means (not shown) trained about the second wheels, and means, such as the face of the box 71, providing a second upper aperture 82 associated with the upper frame and a second lower aperture 84 associated with the lower frame. The carrier means trained about the second wheels carries position-identifying indicia spaced along its length so that the indicia visible through the second upper aperture 82 corresponds to the indicia visible through the corresponding second lower aperture 84.

Turning to FIG. 2, it will be seen that the illustrated carrier means 75, only one of which is described

herein, is an endless means trained about a reduced portion 73 of the wheel 72, under a pin 90 and another pin 92, about a reduced portion of the wheel 74, over a pin 94, under a pin 96, under a pin 98 and then over a pin 100 back to the reduced portion 73. The endless means may be provided, for instance, by strips of tape joined together by elastic pieces such as indicated at 102, 104 to provide the necessary tension.

Identifying letters or numbers or other indicia means 10 may be printed or otherwise placed upon the surface of the carrier means 75 so that the number appearing in the upper aperture 76 also appears in the lower, corresponding aperture 78. For instance, as illustrated in FIG. 1, seam 1 appears in the third pleat and in the number 4 position of that pleat because the number 3 appears in the apertures 76, 78 for seam 1 and the number 4 appears in the apertures 82, 84 for seam 1.

The illustrative embodiment of FIGS. 1 and 2 includes a plurality of third means for registering the amount of a plurality of returns or overlaps at the upper edge portion of the drapery and cooperating control means for determining and registering the proper amount of each return or overlap at the lower edge portion of the drapery, each of the eight illustrated third means and cooperating control means being indicated generally by the reference numeral 110. Each means 110 includes a manually movable wheel or rotor means 111, means such as the face of the box 71, providing an aperture 112 associated with the upper frame 22 and an aperture 114 associated with the lower frame 50. Carrier means 116, similar to the above described means 75, is trained about the reduced portion 118 of each wheel 111 and a corresponding wheel or rotor means 120 as best seen in FIG. 2. Each carrier means 116 carries indicia visible through its associated apertures 112, 114 which are, as viewed in FIG. 1, in vertical registry.

The wheels 72, 80 and 111 extend through vertically elongated slots in the face of the box 71 as mentioned previously. Each of these wheels is a means for moving the carrier means trained thereabout.

The wheels 111 and their associated apertures 112, 114 may be numbered or otherwise identified to correspond to the number of returns or overlaps appearing in a drapery or plurality of draperies installed in the drapery sizer, such numbers or other identification not appearing in the drawings.

The carrier means 116 may carry dimensional information spaced along the carrier means in such a manner that, when a particular dimension for a return or overlap at the upper edge of the drapery is shown in an aperture 112, the desired dimension for the corresponding return or overlap is shown in the corresponding aperture 114 therebelow. The number which appears in the aperture 114, for instance, will show the amount in inches to increase or decrease the return or overlap at the bottom edge portion of the drapery. The illustrated means 110 nearest the left-hand side of the box 71 which may be the means for the first return or overlap appearing on a drapery, shows the number 3 in the aperture 112 and the number 2 in the aperture 114. These numbers may be placed on the carrier means 116 by printing or other such technique. The dimensional numbers placed on each carrier means 116 are positioned such that, for each number

appearing in an aperture 112, the number appearing in the corresponding aperture 114 is a calculated number based upon the spacing and size of pleats and the amount of overlap or return at the upper edge portion of the drapery. Thus, the wheel 111 and the portion of the carrier means 116 visible through the aperture 112 together with the aperture 112 constitute means for registering the amount of return or overlap at the upper edge portion of the drapery while the wheel 120 and the portion of the carrier means 116 visible through the aperture 114 and the aperture 114 constitute cooperating control means for determining and registering the proper amount of overlap or return at the bottom portion of the drapery. In the drapery sizing art, the amount of proper overlap or return at the lower edge of a drapery as compared to the amount at the upper edge is well known and the dimensional numbers are located on the carrier means 116 in accordance with this well known information.

It will be appreciated by those familiar with the drapery sizing art that the box 71 which may be attached to a cabinet wall to extend vertically is proportioned and designed such that the manually movable wheels 72, 80 and 111 as well as the apertures 76, 82, 112 associated with these wheels may be located at a height such that they are conveniently accessible to an operator who is busily engaged in connecting the upper edge portion of a drapery to the upper frame 22. Then, the apertures 78, 84 and 114, which provide the operator information, may be located to be readily accessible and in view of the operator when the operator is busily engaged in connecting the lower edge portion of the drapery to the lower frame 50. This is why I specify that the upper wheels and apertures are associated with the upper frame while the lower wheels and apertures are associated with the lower frame.

Heretofore, an operator of a drapery sizer has not had any means for registering and determining the seam information and the return or overlap information. Such operators have merely connected the upper edge portion of a drapery to the upper frame and then have tried to connect the lower edge portion of the drapery to the lower frame in such a manner that the return or overlap at the lower, right-hand edge of the drapery was what it should be as compared to the return or overlap at the upper, right-hand edge of the drapery. If it was not, then the operator had to take the lower edge portion of the drapery out of engagement with all of the fingers 52, 54 and readjust the overlap of the fingers so that the amount of overlap produced at the lower, right-hand edge of the drapery would be correct. With my equipment, the operator will know that the amount of overlap of the fingers 52, 54 is not correct as soon as the first vertical seam fails to appear at the proper numbered position relative to the lower fingers 52, 54. In other words, the operator does not have to engage the entire lower edge portion of the drapery with the fingers 52, 54 to find out whether or not the fingers have the proper amount of overlap. My system, therefore, has produced extremely advantageous results. In my own drapery cleaning and sizing operation, my system has significantly increased the efficiency of operators. Without my system, a good operator can accomplish 87 pleats per hour. With my system, the same operator can accomplish 116 pleats per hour.

Another advantage of my system is that it is a wonderful training aid for new inexperienced operators of drapery sizers. With my system, a new operator can quickly learn the relationship of pleats, and overlaps or returns at the upper edge portion of a drapery with the folds corresponding to pleats and the returns or overlaps at the lower edge portion of the drapery.

Finally, while I have shown and described a vertical drapery sizer, it will be appreciated that my system is applicable to a horizontal drapery sizer including separable finger carrying frames, one or both frames being horizontally shiftable.

What is claimed is:

1. In combination, a drapery sizer including a cabinet, upper and lower frames disposed in said cabinet, at least one of said frames being shiftable selectively to determine the spacing therebetween for sizing draperies to the proper length, said upper frame carrying a plurality of laterally spaced apart first fingers for engaging the upper edge portion of a drapery and said lower frame carrying a plurality of laterally spaced apart second fingers for engaging the lower edge portion of such drapery, said first fingers defining pleat receiving spaces therebetween proportioned and designed so that adjacent pleats of such draperies are disposed respectively in adjacent spaces, and said second fingers being proportioned and designed to engage therebetween lengths of such lower edge portion corresponding respectively to said pleats, and a seam locating system including indicia means on said second fingers identifying positions thereon corresponding respectively to predetermined positions on such pleats, a plurality of first means for registering the identity of each pleat in which each vertical seam of such a drapery appears, and a plurality of second means for registering the position at which such a seam appears in such a pleat.
2. The combination of claim 1 including a plurality of third means for registering the depth of the return or overlap at the upper edge portion of such a drapery and cooperating control means for determining and registering the proper amount of return or overlap at the lower edge portion of such a drapery, said control means being operatively connected to and operated respectively by said third means.
3. The combination of claim 1 in which each said first means includes a first wheel associated with said upper frame and a first wheel associated with said lower frame, carrier means trained about said wheels, and means providing a first upper aperture associated with said upper frame and a first lower aperture associated with said lower frame, said carrier means carrying pleat identifying indicia spaced along its length so that the indicia visible through said first upper aperture corresponds to indicia visible through said first lower aperture.
4. The combination of claim 3 in which each said second means includes a second wheel associated with said upper frame and a second wheel associated with said lower frame, carrier means trained about said second wheels, and means providing a second upper aperture associated with said upper frame and a second lower aperture associated with said lower frame, the last said carrier means carrying position identifying indicia spaced along its length so that the indicia visible

through said second upper aperture corresponds to indicia visible through said second lower aperture.

5. The combination of claim 4 including a plurality of third means for registering the depth of the return or overlap at the upper edge portion of such a drapery and cooperating control means for determining and registering the proper amount of return or overlap at the lower edge portion of such a drapery, said control means being operatively connected to and operated respectively by said third means.

6. The combination of claim 5 in which each said third means and cooperating control means include a third wheel associated with said upper frame and a third wheel associated with said lower frame, carrier means trained about said third wheels, means providing a third upper aperture associated with said upper frame and a third lower aperture associated with said lower frame, the last said carrier means carrying return or overlap measurement indicia longitudinally spaced along its length so that the indicia visible through said third upper aperture corresponds to indicia visible through said third lower aperture.

7. The combination of claim 2 in which each said first means includes a first manually movable rotor means associated with said upper frame and a first rotor means associated with said lower frame, carrier means connected between said first rotor means to move when said manually movable rotor means is moved, and means providing a first upper aperture associated with said upper frame and a first lower aperture associated with said lower frame, said carrier means carrying pleat identifying indicia spaced along its length so that the indicia visible through said first upper aperture corresponds to the indicia visible through said first lower aperture.

8. The combination of claim 7 in which each said second means includes a second manually movable rotor means associated with said upper frame and a second rotor means associated with said lower frame, second carrier means connected between said second rotor means to move when said second manually movable rotor means is moved and means providing a second upper aperture associated with said upper frame and a second lower aperture associated with said lower frame, said second carrier means carrying position identifying indicia spaced along its length so that the indicia visible through said second upper aperture corresponds to indicia visible through said second lower aperture.

9. The combination of claim 8 in which each said third means and cooperating control means include a third manually movable rotor means associated with said upper frame and a third rotor means associated with said lower frame, third carrier means connected between said third rotor means to be movable when said third manually movable rotor means is moved, means providing a third upper aperture associated with said upper frame and a third lower aperture associated with said lower frame, said third carrier means carrying return or overlap measurement indicia longitudinally spaced along its length so that the indicia visible through said upper aperture corresponds to indicia visi-

ble through said lower aperture.

10. For use with a drapery sizer including upper and lower frames, at least one which is vertically shiftable selectively to determine the spacing therebetween, and each of which carries a plurality of laterally spaced apart fingers for engaging, respectively, the upper and lower edge portions of a drapery, the fingers on the upper frame defining pleat receiving spaces therebetween proportioned and designed so that adjacent pleats are disposed respectively in adjacent spaces and the fingers on the lower frame being proportioned and designed to engage therebetween lengths of such lower edge portion corresponding respectively to the pleats, a seam registering system comprising indicia means arranged to be disposed on the fingers of the lower frame identifying positions thereon corresponding respectively to predetermined positions on such pleats, a plurality of first means for registering the identity of each pleat in which each vertical seam of such a drapery appears, and a plurality of second means for registering the position at which such a seam appears in such a pleat.

11. The invention of claim 10 including a plurality of third means for registering the depth of the return or overlap at the upper edge portion of such a drapery and cooperating control means for determining and registering the proper amount of return or overlap at the lower edge portion of such a drapery, said control means being operatively connected to and operated respectively by said third means.

12. In combination, a drapery sizer including a cabinet, a pair of frames disposed in said cabinet, at least one of said frames being shiftable selectively to determine the spacing therebetween for sizing draperies to the proper length, one of said frames carrying a plurality of spaced apart first fingers for engaging the upper edge portion of a drapery and the other of said frames carrying a plurality of spaced apart second fingers for engaging the lower edge portion of such a drapery, said first fingers defining pleat receiving spaces therebetween proportioned and designed so that adjacent pleats of such drapery are disposed respectively in adjacent spaces, and said second fingers being proportioned and designed to engage therebetween lengths of such lower edge portion corresponding respectively to such pleats, and a seam locating system including indicia means on said second fingers identifying positions thereon corresponding respectively to predetermined positions on such pleats, a plurality of first means for registering the identity of each pleat in which each vertical seam of such a drapery appears, and a plurality of second means for registering the position at which such a seam appears in such a pleat.

13. The combination of claim 12 including a plurality of third means for registering the depth of the return or overlap at the upper edge portion of such a drapery and cooperating control means for determining and registering the proper amount of return or overlap at the lower edge portion of such a drapery, said control means being operatively connected to and operated respectively by said third means.
